Primary Examiner — Ralf Seifert(74) *Attorney, Agent, or Firm* — Banner & Witcoff, Ltd.(57) **CLAIM**

The ornamental design for a gemstone, as shown and described.

DESCRIPTION

FIG. 1 is a top, front, left perspective view of a gemstone showing our new design;

FIG. 2 is a front view thereof, wherein the rear view is identical thereto;

FIG. 3 is a left side view thereof, wherein the opposite, right side view is identical thereto;

FIG. 4 is a top view thereof;

FIG. 5 is a bottom view thereof;

FIG. 6 is a bottom, front, left perspective view thereof;

FIG. 7 is a front view of the design represented in FIGS. 1-6, showing its maximum length, wherein the rear view is identical thereto;

FIG. 8 is a top view thereof; and,

FIG. 9 is a bottom view thereof.

The bracketed portions shown in the FIGS. 1-6 showing a break in the surface represent indeterminate length, up to the length shown in FIGS. 7-9, and form no part of the claimed design.
